UNITED STATES PATENT OFFICE.

JOHN M. FORDEN, OF SPRINGFIELD, ILLINOIS, ASSIGNOR TO EUGENE L. GROSS, JNO. M. FORDEN, JAMES K. WELTER, JOHN O. SLOAN, AND JAMES RAYBURN, OF SAME PLACE.

IMPROVEMENT IN SEED-DROPPERS.

Specification forming part of Letters Patent No. **139,565**, dated June 3, 1873; application filed May 7, 1873.

To all whom it may concern:

Be it known that I, JOHN M. FORDEN, of Springfield, in the county of Sangamon and in the State of Illinois, have invented certain new and useful Improvements in a Seed-Dropper; and do hereby declare that the following is a full, clear, and exact description thereof, reference being had to the accompanying drawings and to the letters of reference marked thereon, making a part of this specification.

The nature of my invention consists in the construction and arrangement of a seed-dropper, as will be hereinafter more fully set forth.

In order to enable others skilled in the art to which my invention appertains to make and use the same, I will now proceed to describe its construction and operation, referring to the annexed drawing, in which—

Figure 1 is a bottom perspective view of my seed-dropper; Fig. 2 is a longitudinal section of the slide; and Fig. 3 is a plan view of a part of the same.

A represents the hopper, and B is the bottom plate of the same, said bottom plate being cut out, as shown in Fig. 1, so as to form the right-angle shoulders *a a* and inclines *b b*, each one of the latter being between two of the shoulders. C represents the seed-slide, which moves back and forth and is within the hopper, provided with a counter-sunk circular recess for the reception of a circular disk or plate, D. This disk is near the circumference provided with six holes, *d d*, at equal distances apart, which holes form seed-chambers. The disk D is attached to a central hub, f, which passes down through a hole made for that purpose in the center of the circular recess in the slide C. Upon the lower end of the hub f, below and against the under side of the slide, is attached a triangular piece, E, upon which are formed or attached three arms, *h h*,

extending from the center through and beyond the corners of the triangle. As the slide is moved back and forth the projecting ends of the arms *h h* operate against the shoulders *a a* of the bottom plate B and turn the triangle E and with it the disk D, the sides of the triangle coming against the inclines *b b* as stops. At the completion of each stroke of the slide C one of the seed-chambers *d* in the revolving disk D comes directly above an aperture, *e*, in the slide and allows the corn in said chamber to fall down through the aperture. G represents a stationary cut-off attached to the top of the slide C and extending over the rotating disk D so as to cover that chamber, *d*, in said disk, which is over the aperture *e* in the slide. This cut-off is fastened to the slide C by a bolt and nut with an elastic washer or nut, *i*, placed on said bolt above the inner end of the cut-off, so as to allow the cut-off to yield or give for any grain of corn that may project out from the seed-chamber. The rotating disk D may readily be removed and another with larger or smaller seed-chambers substituted, so as to drop more or less corn at each stroke, as may be desired.

Having thus fully described my invention, what I claim as new, and desire to secure by Letters Patent, is—

The seed-slide C, provided with an annular recess, in combination with the perforated and rotating disk D, and the stationary cut-off G, all constructed and operating substantially as and for the purposes herein set forth.

In testimony that I claim the foregoing, I have hereunto set my hand this 14th day of April, 1873.

JOHN M. FORDEN.
